TYPEWRITING DEVICE

Roger Marceau Petit, Clichy, France, assignor of two-thirds to Société Dimar and one-third to Société Bar-fred, Casablanca, Morocco, corporations of Morocco

Application April 27, 1953, Serial No. 351,364

Claims priority, application France May 5, 1952

8 Claims. (Cl. 197—17)

My invention relates to operating means in power operated typewriters or similar machines such as calculating and tabulating machines, in which the operative machine element such as a type bar is not controlled directly by an actuating machine element such as a key bar but by an auxiliary operating device interposed between said machine elements. In known machines said auxiliary operating devices were electric or electromagnetic devices which were intricate and expensive.

The object of my invention is to provide operating means of the said type which are inexpensive, simple in construction and reliable in operation.

According to my invention I insert between the machine element to be actuated, for example the type bar, and its operating element, for example the key bar, a flexible connector which in inoperative position is loosely looped around a continuously rotating driving member and which when tightened upon said driving member will effect the desired operational movement for example of the type bar.

The said and other objects of my invention will be more fully understood from the following specification when read with the accompanying drawing in which two embodiments of my invention are schematically illustrated in Figs. 1 and 2, respectively.

My typewriter as illustrated in Figs. 1 and 2, respectively, comprises a platen 1 mounted in customary manner in the machine frame which is not shown in the drawing. A plurality of type bars 3 of which only one is shown are swingingly mounted in the machine frame. Each type bar 3 carrying conventional specific types 2 is pivoted in the machine frame on a pin or the like 4 and is supported in the shown rest position by a stationary pad 5 or the like. A spring 6 attached with one end at 7 to the machine frame and with its other end at 8 to the type bar 3 tends to hold the same in and to return the same into the shown rest position. The type bar 3 is actuated that is swung from its shown rest position into typing position, by a flexible connector 9 which is attached thereto at 10 and may consist of a band or cable preferably made from a flexible synthetic material like nylon.

In the embodiment shown in Fig. 1 said connector 9 stretches from said point of attachment 10 towards a guide pulley 11 to which it may be secured at 16 for example by a screw, continues loosely around a driving pulley 13 and is with its other end at 15 again secured to the guide pulley 11. The driving pulley 13 is mounted upon a continuously rotating shaft 14 driven, for example, by a not shown electric motor and rotates freely in the direction of arrow F within the loop formed by the connector 9 between its points of attachment 15, 16 to the guide pulley 11.

Each type bar 3 is associated with and operated by a key bar 17 which is pivoted at one end at 18 in the machine frame, abuts in rest position against a stop member 38 and carries at its outer end one of the customary specific keys 19. A knee lever comprising a pawl 21 with hook 22 and a control arm 23 is pivoted at 20 upon the

2

key bar 17. The hook 22 cooperates with tensioning means which temporarily tighten the loose loop of the connector 9 about the rotating driving pulley 13 to effect the typing stroke of the type bar 3. As shown in Fig. 1 said tensioning means comprise a rocking member which has the shape of a reversed T and is pivoted in the machine frame on pin 32. The upstanding arm 33 of said T-shaped rocking member supports at its outer end a tension roller 35 pivoted upon axle 34 and said roller 35 when pressed against the looped portion of the connector 9 will tighten the connector upon the rotating driving pulley 13 to be taken along by friction. The cross piece of the T-shaped rocking member which is substantially parallel to the key bar 17 is composed of the arms 27, 28. The end of the arm 27 engages the hook 22 of the pawl 21 and the arm 28 rests upon the support 39 being held in such resting position by the spring 30 which with one end at 29 is attached to said arm 28 and with its other end at 31 to the key bar 17.

20 An eccentric stop member 36 is adjustably mounted in the machine frame upon axle 37 for cooperation with the control arm 23 which releases the hooked pawl 21 from the arm 27 of the tensioning means when the key bar 17 terminates its downward swing movement.

The device illustrated in Fig. 1 will operate as follows:

When the key bar 17 is depressed by exerting pressure upon key 19 the hook 22 of pawl 21 engaging arm 27 of the T-shaped rocking member will cause the same to tilt in clockwise direction about its axle 32 and the roller 35 mounted on the outer end of arm 33 will press against the slackened portion of the connector 9 thus tightening the same upon the rotating driving pulley 13 for frictional cooperation therewith and causing the connector 9 to swing the type bar 3 into typing position relative to platen 1. Meanwhile the depression of the key bar 17 has so far progressed that the control arm 23 strikes the previously adjusted stop 36 causing the pawl 21 to tilt with said arm 23 and to release arm 27 of the T-shaped tensioning member which will immediately return into the shown rest position by the action of spring 30. Thus the tension roller 35 retracts from the connector 9 which resumes its slackened position around the drive pulley 13 and ceases to pull upon the type bar 3 permitting the same to return into the shown rest position by the action of spring 6. When finally the key 19 is released the key bar 17 will swing back into the initial rest position by the action of spring 30 and the hook 22 on pawl 21 will reengage the arm 27 by the action of spring 24 which is attached to said pawl at 25 and to said key lever 17 at 26 readying the device for the next operation.

50 In the modified embodiment illustrated in Fig. 2 the flexible connector 9 embraces loosely the driving pulley 13 by a full turn in the direction of rotation of said pulley as indicated by arrow F. One end of the connector 9 is linked at 19 to the type bar 3 to operate the same in the manner described above with reference to Fig. 1. The other end of said connector 9 is linked at 40 to the left arm of a tensioning lever 41 articulated about axle 41' and mounted above and substantially parallel to the key bar 17. Said left arm contacts in rest position a stationary stop member 51 and is provided with a stud 56 which cooperates with a pawl 54. The other i. e. the right arm of said tensioning lever 41 is connected to the key bar 17 by a spring 43 attached thereto at 42 and 44, respectively. The said pawl 54 is connected to the type bar 17 by a spring 57 which tends to hold said pawl 54 in engagement with said stud 56, said pawl 54 forming one arm of a knee lever of which the control arm 54' is the second arm. A stop 38 limits the upward movement of the key lever 17. The said control arm 54' operates with an adjustable stop member 49 which upon contact will effect a swing movement of said pawl 54 and

will disconnect the same from the said stud 56 so that the spring 43 will return the tensioning lever 41 into its initial horizontal position.

This second embodiment will operate similarly as the first embodiment described before.

When the key bar 17 is depressed by exerting pressure upon key 19 the hooked pawl 54 engaging the stud 56 upon the left arm of the tensioning lever 41 will cause the same to tilt in anticlockwise direction about its axle 41' thus stretching the connector 9, tightening its loop 10 around to continuously rotating driving pulley 13 for frictional cooperation therewith and effecting a swing movement of the type bar 3 into typing position relative to platen 1. Meanwhile the depression of the key bar 17 has so far progressed that the control arm 54' strikes the previously adjusted stop member 49 causing the pawl 54 to tilt with said arm 54' and to release the stud 56 of the tensioning lever 41 which will return into its initial position under the action of spring 43. Thus the pull on connector 9 will cease, its loop will be freed from frictionally contacting driving pulley 13 and spring 6 will return the type bar 3 into the shown rest position. When finally the key 19 is released the key bar 17 will swing back into its shown initial position by the action of spring 43 and the hooked pawl 54 will reengage the stud 56 under the 25 action of spring 57 connecting said pawl 54 and key lever 17 thus readying the device for the next operation.

For good operation of the device it may often be advisable to hold the loose loop of the connector 9 substantially concentrical around the driving pulley 13. This 30 may be achieved by a skeleton frame or cage, formed for example by parallel rods 52, which will confine the said loop and limit its extension.

Also it may be of advantage to localize the slack of the connector 9, while the device is at rest, to the loop surrounding the driving pulley 13. This may be accomplished by elastic means such as a spring 53 attached with its ends to the connector 9 on each side of driving pulley 13. The force exerted by said elastic means 53 upon the connector 9 should, however, remain constantly lower than the effort exerted on type bar 3 by spring 6.

Finally, it will be well understood that the rotational speed of the driving pulley 13 may be variable or adjustable in order to control the rapidity or suddenness of the swing motion of the type bar 3, and that the disclosed operating means may be applied not only to the type bars 45 and key bars, but also to the control of the elevation of the cradle of type bars, to the control of tabulators and to the control of any other movable element of typewriting, calculating and similar machines.

While specific embodiments of my invention have been shown and described in detail to illustrate the application of the principles of my invention it will be understood that my invention may be otherwise embodied without departing from such principles.

What I claim as my invention is:

1. In a power operated typewriter including a drive shaft, a plurality of swingable type bars and of depressible key bars, and operating means between each key bar and each type bar, the improved operating means comprising in combination flexible bandlike connectors each linked with one end to one type bar to effect the typing stroke thereof, a driving pulley for each of said connectors rotating with said drive shaft, each connector loosely wound about its driving pulley in the direction of rotation thereof, tensioning means for each connector actuated by the key bar when the same is being depressed to tighten the connector about its pulley for frictional cooperation to effect the typing stroke of the type bar, and releasing means automatically freeing said tensioning means to loosen the tightened connector from its pulley when the respective key bar is depressed by a predetermined adjustable distance prior to reaching its lowermost position thus permitting the type bar to return into its rest position.

2. A power operated typewriter as claimed in claim 1 wherein at least some of neighboring pulleys of said operating means are integrated into a drum.

3. In a power operated typewriter including a drive shaft, a plurality of swingable type bars and of depressible key bars, and operating means between each key bar and each type bar, the improved operating means comprising in combination flexible bandlike connectors each linked with one end to one type bar to effect the typing stroke thereof; a driving pulley for each of said connectors rotating with said drive shaft; a guide pulley preceding each driving pulley; the other end of the connector attached to said guide pulley leaving a loop or slack loosely embracing the driving pulley in the direction of rotation thereof; tensioning means for each connector actuated by the key bar when the same is being depressed to tighten the said loop of the connector about the driving pulley for frictional cooperation to effect the typing stroke of the type bar; and releasing means automatically freeing said tensioning means to loosen the tightened loop of the connector from the driving pulley when the respective key bar is depressed by a predetermined adjustable distance prior to reaching its lowermost position thus permitting the type bar to return into its rest position.

4. A power operated typewriter as claimed in claim 3 wherein at least some of neighboring guide pulleys and driving pulleys, respectively, of said operating means are integrated into a drum.

5. In a power operated typewriter including a drive shaft, a plurality of swingable type bars and of depressible key bars, and operating means between each key bar and each type bar, the improved operating means comprising in combination flexible bandlike connectors each linked with one end to one type bar to effect the typing stroke thereof; a driving pulley for each of said connectors rotating with said drive shaft; each connector loosely wound about its driving pulley in the direction of rotation thereof; tensioning means for each connector including a three-armed rocking member having the shape of a reversed T; the two-armed cross piece thereof being substantially parallel to the key bar; a tension roller rotatably mounted at least near the free end of the upstanding arm of each rocking member for cooperation with the respective connector; a pawl pivotably mounted on each key bar; said pawl cooperating with one arm of the cross piece of one rocking member to swing and press the tension roller against the connector to tighten the same around its driving pulley; and releasing means for each pawl automatically freeing the same from said cross piece to permit the said rocking member with the said tension roller to return to its initial inoperative position thus reloosening the tightened connector from its pulley when the respective key bar is depressed by a predetermined adjustable distance prior to reaching its lowermost position and permitting the type bar to return into its initial rest position.

6. In a power operated typewriter including a drive shaft, a plurality of swingable type bars and of depressible key bars, and operating means between each key bar and each type bar, the improved operating means comprising in combination flexible bandlike connectors each linked with one end to one type bar to effect the typing stroke thereof; a driving pulley for each of said connectors rotating with said drive shaft; each connector loosely wound about its driving pulley in the direction of rotation thereof; tensioning means for each connector including a three-armed rocking member having the shape of a reversed T; the two-armed cross piece thereof being substantially parallel to the key bar; a tension roller rotatably mounted at least near the free end of the upstanding arm of each rocking member for cooperation with the respective connector; a knee lever pivotably mounted on each key lever, one arm of said knee lever forming an upstanding pawl engaging one arm of the cross piece of the respective rocking member to swing and press

the tension roller against the connector and to tighten the same on its driving pulley; an adjustable stop member cooperating with the other arm of said knee lever when the key bar is being depressed to release the pawl from its engaging position and to permit the said rocking member with the said tension roller to return into its initial inoperative position thus reloosening the tightened connector and permitting the type bar to return into its initial rest position.

7. In a power operated typewriter including a drive shaft, a plurality of swingable type bars and of depressable key bars, and operating means between each key bar and each type bar, the improved operating means comprising in combination flexible bandlike connectors each linked with one end to one type bar to effect the typing stroke thereof; a driving pulley for each of said connectors rotating with said drive shaft; each connector in rest position loosely wound about its driving pulley in the direction of rotation thereof; a plurality of swingable tensioning levers, each lever mounted above and substantially parallel to one key bar; a plurality of flexible bandlike connectors each linked with one end to one type

bar and with the other end to said tensioning lever; a driving pulley for each connector rotating with said drive shaft; a loop in each connector loosely embracing the pulley cooperating therewith; means operated by each key bar to swing the respective tensioning lever in order to tighten the connector around its driving pulley; and releasing means automatically freeing each lever from its outswung position to loosen said loop around its pulley when the key bar is being depressed and thus permitting the type bar to return into its initial rest position.

8. In a power operated typewriter as claimed in claim 1, elastic means localizing the slack of the connector to its portion embracing the driving pulley.
